UNITED STATES PATENT OFFICE.

GEORGE V. CORNELL, OF BOUND BROOK, NEW JERSEY.

DESIGN FOR A CASING FOR A GAME APPARATUS.

SPECIFICATION forming part of Design No. 33,153, dated September 4, 1900.

Application filed June 28, 1900. Serial No. 21,994. Term of patent 3½ years.

To all whom it may concern:

Be it known that I, GEORGE V. CORNELL, a citizen of the United States, residing at Bound Brook, in the county of Somerset and State of New Jersey, have invented and produced a new and original Design for the Casing of a Game Apparatus, of which the following is a specification, reference being had to the accompanying drawings, forming a part thereof, and in which—

Figure 1 is a top view of a casing for a game apparatus embodying and incorporating my design. Fig. 2 is a perspective view of same, and Fig. 3 is a central vertical section of same on the dotted line 3 3 of Fig. 1.

The leading feature of my design consists of the form and configuration of the said casing, substantially as shown.

In the drawings, A designates the tubular

portion of the casing, B a disk portion of the 20 said casing and having vertical circular apertures C, surrounding a central vertical aperture D, and E a tubular portion of the said casing, said portion E being concentric with the portion A and central aperture D and 25 the whole being substantially of the form and configuration shown.

What I claim is—

The design for a casing for a game apparatus, substantially as shown and described. 30

Signed at Bound Brook, in the county of Somerset and State of New Jersey, this 25th day of June, 1900.

GEORGE V. CORNELL.
